CLAIM

The ornamental design for a combined handle and escutcheon with lock, as shown and described.

DESCRIPTION

FIG. 1 is a perspective view of a combined handle and escutcheon with lock showing my new design;

FIG. 2 is a reduced front elevational view thereof;

FIG. 3 is a reduced rear elevational view thereof;

FIG. 4 is a reduced left side elevational view thereof,

the right side being a mirror image;

FIG. 5 is a reduced top plan view thereof;

FIG. 6 is a reduced bottom plan view thereof.

Fig. 1
